United States Patent Office.

JOSEPH VENET, OF NEW YORK, N. Y.

Letters Patent No. 97,836, dated December 14, 1869.

IMPROVED RETICULE WICKER-BASKET.

The Schedule referred to in these Letters Patent and making part of the same.

To all whom it may concern:

Be it known that I, JOSEPH VENET, of the city, county, and State of New York, have invented a new and useful Improvement in Reticule Wicker-Baskets, of which the following is a specification.

The nature of my invention consists in the employment and use of a metallic wire, in such manner as to form three or more ribs of the wicker-work, said metallic ribs passing around the body and cover of the basket, and forming metallic holders for the handles of the basket, and hinges, by which the cover is united to the body of the basket, and also forming the loop and staple-connection for reception of the lock, which renders the basket safe and durable, besides enhancing its commercial value, as I will further explain by reference to the drawings, of which—

Figure 1 represents a wicker-basket with my invention applied to it, and

Figure 2, a sectional elevation of same, with cover raised.

In the said drawings—

A indicates the body,

B, the cover, and

C C, the handles of the basket.

D E indicate the ribs and interlacing of the wicker-work, and

G G G, the metallic ribs, which run through the body of the basket.

These ribs are carried under the bottom and up the

sides of the body of the basket to the mouth, and similar ribs g' g', are carried through the cover of the basket.

The outer ribs G G form holders h h, for reception of the handles C C, in front, and holders i i for the reception of said handles in rear of the basket, and being continued above the mouth, said ribs, with similar ribs g g', running through the cover B, form the hinges J J, by which the cover is united to the body of the basket. (See fig. 2.)

The middle rib G', which, like the other ribs, passes round the body of the basket, is united to the ribs G G in front and rear of the basket, near the mouth, and forms a staple, k, in front, for reception of a hasp, l, formed on the rib g', which runs through the cover of the basket, and also for reception of the lock m.

Having described my invention,

What I claim, is—

A reticule wicker-basket provided with metallic ribs G G' g, &c., which form the holders h i for the handle, hinges J J for the cover, and loop and staple k l for the lock, as a new article of manufacture, substantially as set forth.

In testimony whereof, I have hereunto set my signature, this 15th day of October, A. D. 1869.

JOSEPH VENET.
